Attorneys

UNITED STATES PATENT OFFICE.

JOHN AHLEN, OF FARGO, NORTH DAKOTA:

PLANE ATTACHMENT.

Application filed March 18, 1924. Serial No. 700,179.

To all whom it may concern:

Be it known that I, JOHN AHLEN, a citizen of the United States, residing at Fargo, in the county of Cass and State of North Dakota, have invented certain new and useful Improvements in a Plane Attachment, of which the following is a specification.

This invention relates to wood working tools, and the primary object of this invention is to provide a plane having a novel means for lifting the blade or iron thereof above the work upon the return movement of the plane, thereby preventing undue wear upon the blade and the necessity for raising the whole plane above the work on the back stroke, thus permitting the smooth operation of the plane and the relieving of the user of the plane from undue exertion.

A further object of the invention is to provide a shoe carried by the plane in such a manner that the blade or iron of the plane will be spaced from the work on the back stroke of the plane, and when the plane is in a position of rest, thereby preventing injury to the blade and the marring of the object upon which the plane is laid.

A further object of the invention is to provide a double faced shoe pivotally carried by the plane which is normally urged into an operative position, so that the same will always be in work engaging position without any attention of the user of the plane.

A still further object is to provide a reversible pivoted shoe carried by a plane for the above described purpose, which will be durable and efficient in use, one that will be simple and easy to manufacture, and one which can be easily associated with any type of plane.

With these and other objects in view, the invention consists in the novel construction, arrangement and formation of parts, as will be hereinafter more specifically described, claimed and illustrated in the accompanying drawings, forming a part of this specification, in which:

Figure 1 is a side elevation of a plane, partly in section, showing the improved device incorporated therewith and in position for holding the blade or iron of the plane spaced from the work.

Figure 2 is a fragmentary plan view of the plane partly in section, showing the improved device incorporated therewith.

Figure 3 is a fragmentary side elevation of the plane partly in section, showing the improved device incorporated therewith, and in an inoperative position.

Referring to the drawing, wherein similar reference characters designate corresponding parts throughout the several views, the letter A indicates a plane and B the improved blade spacing device therefor.

The plane A is of the usual or any preferred construction and style, and includes the stock 5, the handles 6 and 7, blade holding and adjusting means 8, and the blade or iron 9. The stock 5 is provided with a transversely extending slot 10, forwardly of the transverse center thereof, and preferably directly below the blade holding and adjusting means 8. As shown the stock 5 is made of metal, and is provided with the upturned side flanges 11.

The improved blade raising device B includes a shoe 12, which is adapted to extend transversely of the stock 5. This shoe 12 includes the shank 13 and the cam plate 14. This plate 14 is curved transversely as clearly shown in Figures 1 and 3 of the drawings, and extends outwardly from the opposite side of the shank 13 so as to form a double face. This permits the reversing of the shoe 12 when one face thereof becomes worn or broken. The upper end of the shank 13 is provided with a barrel 15 which receives the transversely extending pivot pin or stub shaft 16. This pivot pin or stub shaft 16 has its terminals secured in any preferred manner to the side flanges 11 of the stock 5, and as shown, the ends thereof are reduced and fitted in suitable openings 17 in the flanges 11. If so desired, one of the reduced ends of the pivot pin or stub shaft 16 may be threaded into one of the openings 17, while the opposite end may be provided with a screw head. The cam face 14 is adapted to normally extend through the slot 10, and the rear wall of this slot is curved as at 18, to conform to the curvature of the active face of the cam, while the opposite wall of the slot may terminate abruptly as at 19, for forming a stop for the forward edge of the cam plate.

In order to insure that the shoe will be normally held in an operative position, the spring 20 is provided. This spring 20 is coiled around the stub shaft or pivot pin 16 adjacent to the terminals thereof, and has its intermediate portions bearing against the

shank 13 of the shoe at its terminals bearing against the stationary portion of the stock 5, as indicated by the numeral 21.

In use of the improved plane, it can be seen that upon forward or working stroke of the plane, the shoe 12 will be forced upwardly against the tension of the spring 20 into the slot 10 and out of the way of the work. Thus permitting the iron or blade 9 to engage the work. Upon the back or return stroke of the plane, however, the shoe will ride below the lower surface of the stock of the plane and engage the face of the work, and thus hold the active face of the blade 15 above the work and thus prevent injury or undue wear thereon.

It can be seen that when the plane is laid upon an object, the shoe will be in operative position below the lower face of the stock 5, 20 and thus hold the blade or iron 9 above the object. Owing to the position of the shoe forwardly of the transverse center of the shoe, the plane will rest upon the rear edge of the stock and on the shoe 12, and thus absolutely prevent the blade from engaging the object and injuring the same.

In case one face or edge of the cam surface 14 of the shoe 12 becomes broken or mutilated, it is merely necessary to remove the 30 stub shaft or pin 16 and reverse the position of the shoe in the plane and replace the pin or stub shaft 16. This will present the new or unused edge of the shoe to the work.

From the foregoing description, it can be seen that an exceptionally simple and automatic device has been provided for holding

the cutting edge of a blade of the plane above the work upon the back stroke of the plane, and when the blade is laid in a position of rest.

40

Changes in details may be made without departing from the spirit or scope of this invention; but,

I claim:

1. In a plane, the combination with a stock 45 including a sole and side walls, the sole having a transverse slot therein, a shoe including a shank, a cam plate, and a hinge barrel, the cam plate being adapted to protrude through the slot, a pivot pin detachably carried by the side walls of the stock positioned in the hinged barrel, and a spring coiled around said pivot pin and arranged to engage the shoe and the stock.

2. In a plane, the combination with a stock 55 including a sole and side walls, the sole having a transverse slot therein, and a blade, of an attachment for normally holding the blade above the work when the plane is moved in one direction and when in position 60 of rest comprising a cam plate disposed transversely across the stock for projecting through the slot, said plate being curved transversely, a shank formed longitudinally of the plate and disposed intermediate the longitudinal edges thereof, a hinged barrel formed on the upper edge of the shank, the side walls having openings formed therein and attached in advance of said slot, and a hinged pin extending through said openings 65 and the hinged barrel.
